MECHANISM FOR CASTING METALS IN
INVESTMENT MATERIAL

George A. Yantis, Elma, Wash.

Application April 27, 1938, Serial No. 204,617

13 Claims. (Cl. 22—57.1)

My invention relates to a mechanism for carrying out the process of casting metals in investment material. More particularly, my invention relates to a device which will control the conditions of casting to carry out a process of casting metals in investment material so that the shrinking of the metal upon cooling will not provide a molded product of a size different from that desired.

10 My invention will be described as applied to dental castings, as inlays, crowns, partial dentures etc. although the invention is not to be limited to any such specific application, but is to be co-extensive to all applications involving like conditions.

15 Heretofore great difficulty has been experienced in the production of accurate castings. A perfect impression in wax, of a cavity in a tooth may be obtained, but, because of the shrinkage of the 20 gold from the molten to the solid state, difficulty in accurately reproducing the wax mold of the cavity into gold is encountered.

25 A primary object of my invention is to provide the mechanism for carrying out a method of casting the metals so that the cast product will be of the desired size.

30 Dental gold is usually alloyed with other metals to give it required hardness and wearing qualities. When this dental gold is melted or is heated in the presence of air, as for tempering or soldering, the metals which are alloyed with the gold will oxidize, forming a scum on the outside of the 35 metal. This oxidation tends to retard free flow of the metal, leaves the casting or heat treated part dirty and coated on the outside so that it must be cleaned by a pickling process using acid, and further changes the percentages of the different 40 metals in the alloy. In accordance with common practice this oxidizing of the metal and the objectionable results of such oxidation are overcome, to a certain extent but not entirely, by the use of fluxes which prevent some of the oxidation and make the metal flow more freely when molten and which facilitate soldering of the metal.

45 In accordance with this invention I provide for heating and melting the metal in the presence of a gas which contains no free oxygen and is herein termed an inert gas thus completely preventing oxidation, insuring a product which is 50 always clean and does not need to be pickled or cleaned, insuring a product which flows freely, and tending to produce more accurate work due to the fact that there is no change in the percentages of metals in the alloy and no coating of 55 oxidized metal on the exterior of the finished

work. Also excluding the air and casting in the presence of an inert gas makes it possible to fuse molten metal to solid metal and thus obviates the necessity of soldering different pieces together after casting. This saves time and labor.

5 In casting metals in investment material the expansion of a given investment material will vary in proportion to the temperature, it being common knowledge that some investment materials have a different coefficient of expansion 10 than others. Also the molten metal will have a certain amount of shrinkage upon cooling. In dental casting it may be desirable to allow a slight amount of clearance for cement or to make a part, as a dental crown which is to fit over a 15 tooth, slightly oversize, or to make a part which is to fit into a cavity, such as an inlay, slightly undersize to insure proper clearance. To accomplish this it is desirable to be able to determine very accurately the temperature of the investment in which the casting is being made. It is an object of my invention to provide a combined 20 furnace and casting machine having pyrometer means for accurately indicating the temperature of the investment material and having variable 25 heat means for heating the investment material to any desired predetermined temperature, thereby making it possible to have the investment material at precisely the correct temperature for the casting of the metal in each individual case 30 and in this way insuring the production of better castings.

35 Another object of my invention is to provide a combined furnace and casting machine in which the metal is electrically melted, thus avoiding the use of oxidizing torch flames on the metal and keeping the metal clean and pure.

40 Another object of the invention is to provide a furnace adapted for the reception of an investment ring containing investment material and having a crucible movable into and out of registration with the end portion of said investment ring and adapted to deliver molten metal directly 45 into a mold cavity in the investment material in said ring.

45 Another object of the invention is to provide a combined furnace and casting machine having means for admitting an inert gas under pressure into the crucible where the gold or like metal is being melted to drive out the air prior to the 50 melting of the metal and to help force the metal into the mold after it is melted.

55 Another object of this invention is to provide a combined furnace and casting machine in which both the furnace portion, and the crucible por-

tion are capable of independent use for heat treating or tempering metal parts or for baking porcelain parts.

The above mentioned general objects of my invention, together with others inherent in the same, are attained by the devices illustrated in the following drawings, the same being preferred exemplary forms of embodiment of my invention, throughout which drawings like reference numerals indicate like parts:

Figure 1 is a vertical sectional view, with parts in elevation of two furnaces of different size and a crucible means constructed in accordance with this invention, showing investment rings of different size, each with investment material there-in disposed within said furnaces and showing a crucible movable into operative relation with respect to either furnace and adapted to deliver molten metal into a mold cavity in the investment material in the selected furnace;

Fig. 2 is a vertical sectional view of a modified form of this invention;

Fig. 3 is a sectional view substantially on broken line 3—3 of Fig. 2;

Fig. 4 is a vertical sectional view of another modified form of the invention;

Fig. 5 is a view partly in elevation and partly in section substantially on broken line 5—5 of Fig. 4;

Fig. 6 is a fragmentary sectional view on a larger scale than Fig. 4, showing a valve device embodied in the apparatus shown in Fig. 4;

Fig. 7 is a detached edge view of a door applicable to the retort shown in Fig. 4;

Fig. 8 is a sectional view of another modified form of the invention;

Fig. 9 is a sectional view of still another modified form of the invention;

Fig. 10 is a plan view of a base member adapted to be used in preparing an investment within an investment ring;

Fig. 11 is a sectional view of said base member substantially on broken line 11—11 of Fig. 10;

Fig. 12 is a fragmentary plan view of the under side of a top plate member;

Fig. 13 is a diametrical sectional view of said top plate member in inverted position and in operative relation to an investment ring, a fragment of which is shown;

Fig. 14 is a plan view of the upper side of a sprue wire holder;

Fig. 15 is a sectional view of a modified form of sprue wire holder;

Fig. 16 is a detached elevation of a U shaped sprue wire;

Fig. 17 is an end view of an investment ring with positioning notches therein;

Fig. 18 is a fragmentary side view of said investment ring; and

Fig. 19 is an exploded sectional view of a table.

Referring to Figure 1 of the drawings, 20 designates a base and 21 and 22 two furnaces of refractory material mounted on said base at equal axial distances from an upright tubular post 23 on the base. The refractory furnaces 21 and 22 each have a lining 24 of heat insulating material provided with grooves 25 within which electric heating coils 26 are disposed. I have shown an investment ring 27, containing 65 investment material 28, disposed within the lining 24 of each furnace. Also I have shown in the investment material 28 in each ring 27, a cavity 31 which is adapted to receive molten metal. A pyrometer member 30 having the usual 70 pyrometer devices therein extends from the base 75

28 upwardly through the bottom of the furnace housings 21 and 22 and lining 24 and has the tip portion thereof positioned in contact with the investment material 28. Connecting wires 32 and 33 connect the pyrometer member 30 of 5 the respective furnaces 21 and 22 with terminals 34 and 35, which are adapted to be engaged by a pivoted contact arm 39. The arm 39 is connected by a wire 36 with dial and pointer means 37 on which the temperature of the investment 10 material in either furnace may be registered. Tension springs 38 yieldingly support the pyrometer members 30 in such a manner as to permit said members to be pushed downwardly by contact with the investment material, thus 15 insuring firm contact between the pyrometers and the investment material. Friction means or other yielding means may be used in place of springs 38.

A cover member 40 of heat refractory material 20 is connected by hinge means 40' with the smaller furnace 21 and is adapted to close the opening in the top end portion of the said furnace 21 when said furnace is not in use. A fragment of this cover member 23 is shown in 25 an open position in Fig. 1. A separable and removable cover member 41 is provided for the larger furnace 22. Either type of cover could be used on any types of furnace described.

Preferably the heating coils 26 in the furnaces 30 21 and 22 are respectively connected by suitable conductor means shown diagrammatically by 42 and 43 with multiple heat switches 44 and 45. These devices provide for varying the amount of heat supplied to the furnaces, but, as said 35 devices are of old and well known form, they are not herein shown and described in detail. Any other type of heat control can be used in the place of the switches or in conjunction with them.

Extending upwardly from the base 20 between the two furnaces 21 and 22 is the tubular support 23 upon which a bracket arm 46 is slidably mounted for longitudinal and angular movement. A screw 47 serves to lock the bracket arm 46 45 in any desired vertical or angular position on the upright support 23. An extension bracket 48 is rotatably disposed within the bracket arm 46 and a screw 50 prevents disengagement of arm 46 and bracket 48. A crucible housing 51, 50 of refractory material, is secured to the extension bracket 48 and is adapted to be positioned on either of the furnaces 21 or 22. In Figure 1 this crucible housing 51 is positioned on the furnace 21 in the position it will occupy when 55 casting is being done. The crucible housing 51 has a recess of inverted U shape extending from the bottom portion thereof upwardly, and in this recess is a lining 52 of porcelain or like material within which suitable electric heating 60 element means 53 is embedded. A crucible 54, preferably of semi-cylindrical shape, is mounted within the lining 52 on pivot means 55. This pivot means 55 is positioned near the open upper end portion of the crucible so that said crucible 65 will tend to hang by gravity in the position shown in Figure 1. A plan view of a crucible similar to the one shown in Figure 1 is shown in Fig. 3 and the parts therefore correspondingly numbered. The crucible 54 is externally provided adjacent the open top portion thereof and at substantially right angles to the axis of the pivot means 55 with an outwardly projecting vane 56 which is positioned within an arcuate groove 57 in the wall of the lining 52. A pas- 70 75

5 sageway 58 for inert gas extends downwardly in the crucible housing 51 and is thence curved inwardly and upwardly in substantially J shape and extends through the lining in substantially the manner shown in Figure 1 so that a blast 10 of fluid, such as inert gas, may be discharged into the crucible chamber and against the vane 56 to angularly move the crucible on the pivots 55 and dump the contents thereof.

10 Preferably a flexible tubular conduit 60 is connected with a suitable source of supply of inert gas, not shown, and extends upwardly through the tubular post 23 and thence to pipe means 61 which communicates with the passageway 58 so 15 that inert gas under pressure may be supplied to the passageway 58. A valve 62 is provided for controlling the flow of this inert gas.

15 Suitable electrical conductor means 63 preferably extends from a multiple heat switch 64 on the base 20 to the electric heating element 53 in the crucible lining whereby a variable or controlled heat may be provided for the crucible. A pyrometer 65 is provided in the crucible housing 51 and is connected by a wire 66 with a contact member 67 which is adapted to be engaged by the contact arm 39 so that the heat of the crucible may be read on the dial and pointer means 37, the wire 67 passing through tubular post 23.

20 The showing of the several pyrometers and means for reading the temperatures registered thereby is somewhat diagrammatic, it being understood that standard pyrometer mechanism is used and that the arrangement is such as to 25 make it possible to selectively read the temperature registered by any pyrometer member when the contact arm 39 is placed on the contact member 34, 35 or 67 connected with that pyrometer member.

25 In Figs. 10 to 18 inclusive I show certain preferred types of investment rings 27 and devices used in connection therewith for facilitating the handling of the investment preparatory to casting. To insure the proper centering of the investment rings 27 within the furnaces I provide a 30 plurality of V shaped notches 68 in both ends of the rings 27, see Figs. 17 and 18. I have shown four notches 68 in each end of each ring 27 but it will be understood that this centering 35 can be accomplished with two of such notches 68, provided they are not diametrically opposite to each other, or with any desired number of said notches more than two. Preferably the notches 68 are in duplicate in the two ends of the rings 40 27 so that the rings 27 are reversible.

45 For use in connection with the notched investment rings in preparing an investment, I preferably provide a top plate 70, Figs. 12 and 13, and a base plate 71, Figs. 10 and 11. The base plate 50 71 preferably is of inverted cup shape as shown in Fig. 11 and has a centrally positioned pin 72 frictionally held in the plate and manually adjustable longitudinally, to form, in the investment material, an opening of correct size to receive the pyrometer 30. Obviously the top and 55 bottom plates may be duplicates with a central hole the size of the hole 75 in plate 70 and a bushing, not shown, may be used on pin 72 to fit within hole 75 which is of larger diameter than pin 72. The base plate 71 has a plurality of radially extending ribs or tongues 73 of inverted V shape on the top side thereof and the top plate 70 has a plurality of correspondingly positioned ribs or tongues 74. The top plate 70 also has a 60 central opening 75 for the reception of a shank 76

65 on a semi-spherical manifold sprue wire holder 77, which can be formed of resilient material, such as rubber. This sprue wire holder 77 has a plurality of slots 78 in the convex side thereof within which sprue wires may be inserted and held for the purpose of supporting wax molds or impressions that are to be embedded in investment material 28 within an investment ring 27. Preferably U shaped sprue wires 80 of the form shown in Fig. 16 are used, with the ends of the U shaped wires 80 embedded in the wax impressions or molds 82 to be supported and the curved portions thereof inserted in the slots 78. The slots 78 may be arranged as shown in Fig. 14 and are preferably divergent so that several sprue members 80 may be supported in diverging relation by one sprue wire holder 77.

70 Fig. 15 shows a modified form of sprue member support 81 which is similar to the sprue member support shown in Figs. 13 and 14, except that the centering shank 76 thereof is omitted and the said sprue member support 81 depends entirely on vacuum cup action to hold it in place. When a sprue member support 81 of the form shown in Fig. 15 is to be employed, the top plate, not 75 shown, with which it is to be used will be without any central perforation and will be of glass or porcelain or like material to which a vacuum cup will adhere.

75 In setting up an investment for casting, the top plate 70 is preferably supported horizontally in an inverted position, as shown in Fig. 13. The wax impression or mold 82, Fig. 13, having been properly prepared is supported on one or more suitable sprue wires 80, which are held in the slots 78 in the sprue wire support 77 and the sprue wire support 77 is supported as shown in Fig. 13 by the inverted top plate 70. One end of the investment ring 27 is placed on the plate with the ring 27 approximately centrally of the plate 80 70 and the wax impression 82 substantially centrally within the ring 27 and said ring 27 is moved angularly and laterally until the notches 68 in the ring 27 fit over the tongues 74 on the plate 70 and the ring 27 is properly positioned. The investment ring 27 is then filled with plastic investment material so as to properly embed the wax impression 82 in the investment. The base member 71 is then inverted, placed on the ring 27 and adjusted so as to properly center it and the pin 72 is then pressed into the soft investment material a desired distance to make a hole for the future entrance of a pyrometer tip. After the investment material has hardened sufficiently, the entire assembly comprising the ring 27 and the top member 70 and the base 71 may be turned right side up, the top member 70 together with the sprue wire holder 77 and sprue wire 80 removed, and the investment ring 27 separated from the base 71 and made ready for 90 the casting operation.

95 The V shaped ribs 73 on the base plate member 71 will leave V shaped radial grooves in the investment material in line with the notches 68 in the ends of the investment rings 27 and these 100 grooves will fit over correspondingly positioned V shaped ribs 83 in the bottom portion of the furnaces when the rings 27 with investment therein are placed in the furnaces, thus insuring proper positioning of the rings 27 in the furnaces. Preferably the height of the ribs 83 in the bottom portion of the furnaces is greater than the depth of the notches 68 in the end of the investment rings and the corresponding notches in the adjacent investment material so that the investment ring 75

and investment material will be spaced a short distance above the bottom of the furnace to provide for a free escape of air which is driven out of the crucible and furnace when the inert gas under pressure is admitted. This air is driven off through the porous investment material and escapes up past the investment ring and out through a suitable opening between the top portion of the furnace housing and the bottom portion of the crucible housing 51. Preferably the crucible lining 52 extends downwardly far enough so that it engages with the investment material in the adjacent ring 27 and forms a seal to retard the escape of inert gases at this location. It is to be noted that the sprue wire holder 77 will always form a spherical depression 84 in the investment material at the top of an investment ring, which depression does not reach entirely to the walls of the investment ring even in the instance of the smallest investment ring used. It is also to be noted from Fig. 13, which shows the smallest ring, that the V shaped ribs 74 on the top plate 70 do not extend inwardly entirely to the sprue wire holder 77. For this reason the radial grooves left in the investment will terminate short of the spherical depression 84, leaving an ungrooved ring of investment material to make sealing contact with the end portion of the lining 52. This is true both for the smaller investment rings, as shown in the furnace 21 and the larger rings, as shown in the furnace 22 in Fig. 1. It is to be noted that the investment ring 27 shown in Fig. 13 is a ring of small size while the ring 27 shown in Figs. 17 and 18 is of intermediate size and the ring 27 shown in the furnace 22 in Fig. 1 is of large size.

When the sprue wires are withdrawn from the investment material and wax impressions 82, they leave the wax impressions 82 in the investment material and leave one or more channels 85 through which molten metal may flow into the cavity which is left after said wax impressions are melted out of the investment material.

The two furnaces 21 and 22 are positioned with their axes at equal distances from the center of the tubular post 23 so that the crucible assembly, which is angularly movable about the tubular post 23, will register correctly with either of said furnaces. Obviously only one furnace or more than two furnaces may be provided on the base 20 if desired. After an investment has been properly prepared it is placed in one of the furnaces 21 or 22 and will be correctly centered therein by the radial ribs 83 in the furnace. An amount of gold alloy sufficient for the casting to be done is placed in the crucible 54. This insertion of the gold alloy may be easily accomplished by loosening the screw 50 and angularly moving the crucible assembly on the bracket extension 48 far enough to afford access to the interior thereof. At the time this is done the crucible assembly will be elevated on the tubular post 23 and preferably will be angularly positioned so that it will not be in registration with either furnace. After the metal, such as gold alloy, which is to be melted has been placed in the crucible 54 the crucible assembly will be angularly moved on shank 48 back into the upright position shown in Fig. 1, then angularly moved on post 23 to a position directly above and coaxial with the furnace to be used and then lowered onto or into said furnace into operative casting position. It is to be noted that the crucible housing 51 will be positioned slightly above the furnace 21 when in casting position relative

to furnace 21 and will enter a short distance into lining 24 of furnace 22 when in casting position relative to furnace 22.

After a properly prepared investment has been placed in a furnace, the furnace is initially heated up to vaporize and evaporate the wax impression and leave a proper cavity in the investment and to bring the investment up to proper temperature. This may be done either with the cover of the furnace closed or with the crucible assembly 10 in place on top of the furnace. The pyrometer 30 will record accurately the temperature of the investment, thus making it possible to bring the investment up to any desired temperature to secure a desired expansion of the same.

After the crucible housing has been operatively positioned as respects the furnace being used, and preferably just before the heating of the metal to be melted begins, the valve 62 is opened a slight amount to admit just enough inert gas to drive 20 out the air and fill the crucible chamber and cavities in the investment with inert gas. The metal to be cast, such as gold alloy, is thus heated up and melted in the presence of a gas free from oxygen so that no oxidizing thereof can take 25 place. After the temperature of the crucible, as indicated by pyrometer 65, has been raised sufficiently high to insure that the metal or alloy is properly melted and ready for casting the operator quickly opens the valve 62 enough to discharge a blast of inert gas through the passageway 58 and against the vane 56. This angularly moves the crucible 54 through an angle sufficient to dump the molten metal from the crucible into the spherical depression 84 in the top portion of 35 the investment. At the same time the pressure of inert gas within the crucible and above the investment rapidly rises and aids gravity by tending to drive the molten metal into the mold, thus insuring a perfect casting made under accurately 40 controlled temperature and expansion conditions of the investment and in the absence of oxygen. Proper casting temperature of the metal may be insured by a reading furnished by pyrometer 85, or a sight opening means of the form shown at 45 155, Fig. 8, may be provided to permit observation of the metal, or both the pyrometer and the sight opening may be used.

Fig. 2 shows mechanism which differs somewhat from that in Figure 1, but which provides 50 for casting in the absence of oxygen and under the same accurately controlled temperature conditions. In Fig. 2 I show a furnace 86 similar to furnaces 21 and 22 and having correspondingly numbered parts. A crucible housing 87 is hinged 55 to furnace 86 by hinge means 88. This hinge means is preferably capable of being easily disconnected, so that crucible housing 87 can be used interchangeably with furnaces of different size. Also detachment of crucible housing 87 60 makes it possible to use a door or cover plate on the furnace 86. A readily detachable fastening means 90 is provided substantially opposite the hinge means 88 to cooperate in securing the crucible housing to the furnace. The crucible housing 87 has a recess 91 in the bottom portion thereof and has a cylindrical passageway 92 extending from the top downwardly and intersecting said recess. A crucible lining member 93 is longitudinally movable in the recess 91 and has 70 a shank 94 extending into the passageway 92. Devices for moving this crucible lining 93 are connected with the outer end portion of the shank 94. The means herein illustrated for accomplishing this movement comprises a rotatable 75

hand wheel 95 retained in position and rotatably connected with the crucible housing 87 by split collar means 96 secured to the housing 87 and fitting into a groove 97 in the hand wheel 95. 5 The hand wheel 95 is threaded onto a shank 98 which is relatively rotatively secured by a split collar 100 and nut 101 to the end portion of the shank 94 so that rotation of the hand wheel 95 will longitudinally move the lining 93 and parts 10 94 and 98 connected therewith. This provides for adjusting the lining member 93 to properly engage with the investment material in investment rings of different size. A position which the end of lining member 93 may occupy to 15 engage with the investment material in a small ring is shown by dot and dash lines in Fig. 2. The lining member 93 has a crucible 54 pivotally mounted therein by pivot means 55 and adapted to be angularly moved to dump molten metal 20 therefrom by a blast of inert gas under pressure discharged from a passageway 58 against a vane 56, all as previously described in connection with Fig. 1, in which corresponding parts are correspondingly numbered. The passageway 58 in 25 Fig. 2 is formed entirely within the lining 93 and shank 94 and communicates with a similar passageway 102 in the shank 98. Passageway 102 is connected with conduit means 103 for the supply of inert gas under pressure, said conduit 103 having a valve 104. Aligned passageways 105 30 and 106 are provided in shanks 94 and 98 for the entrance therethrough of electric current supply wires to the heating means in the lining member 93.

35 The operation of the apparatus shown in Fig. 2 is similar to the operation of the apparatus disclosed in Figure 1, except that the crucible assembly is mounted and handled in a different manner and the lining member 93 which carries the crucible is adjustable to engage with investment 40 in rings of varying size.

45 Figs. 4 to 6, inclusive, show a device in which the crucible assembly is pivotally mounted and the furnace is hinged to the crucible and the molten material is discharged by gravity in response to a change in angular position of both the crucible assembly and the furnace, which, at the same time, admits the gas.

50 Figs. 4-6 show a crucible housing 107 having a transverse tube 108 embedded therein near one end. The tube 108 is pivotally mounted on a horizontal tubular bearing member 110 which is supported in upright supports 111 and also serves as a conduit for inert gas delivered thereto 55 through conduit means 112 having a control valve 113 therein. The crucible housing 107 has a lining 114 therein which is recessed for the reception of a crucible 115. The lining 114 has electric heating means 116 embedded therein. 60 Preferably the crucible 115 is removable through the open end portion of the lining and the rear edge portion of said crucible is engaged behind a hook like retaining member 117 in the lining 114 when said crucible is operatively positioned 65 within the lining 114.

70 A passageway 118 for the inlet of inert gas under pressure extends from the tube 108 to the chamber within the lining 114. A port 120 in the tube 108 registers with the passageway 118. Another port 121 in the tubular bearing member 110 is positioned so that it may register with the port 120 as shown in Fig. 6, or may be angularly offset as respects the port 120 as shown in Fig. 4, depending on the angular position occupied by 75 the crucible housing 107. A perforation 122 of

small size in the member 110 is positioned to register with the port 120 in the tube 108 when the crucible housing 107 is in a generally horizontal position, as shown in Fig. 4. The purpose of this small perforation 122 is to permit a small amount of inert gas under pressure to flow into the chamber in lining 114 to drive out the air and surround metal in the crucible during the melting process. A loose fit of member 110 in tube 108 will accomplish the same function. The purpose of the port 121 is to permit a free flow of inert gas under pressure for driving the molten metal into the mold cavity as soon as said molten metal is discharged from the crucible by reason of the crucible housing 107 and furnace, attached thereto, swinging from the horizontal position shown by full lines in Fig. 4 to the vertical position shown by dot and dash lines. 15

20 A furnace 123 is connected with the crucible housing 107 in end to end relation with respect thereto by hinge means 124 and adjustable securing means 125. The furnace 123 has a lining 126 provided with electric heating means 127 which is provided in the bottom portion as well as in the side portions of said lining. An adjustable 25 bottom plate 128 is provided in furnace 123 to adjustably support investment rings of different sizes in engagement with the inner end portion of the crucible lining 114. This makes the casting device shown in Figs. 4 to 7 adaptable for the 30 reception of rings of different sizes. The bottom plate 128 has a shank 130 thereon which is seated within a screw member 131. The member 131 is threaded into a fitting 132 which is secured to the furnace housing 123. A pyrometer member 35 30 enters through the shank 130 and contacts the investment material 28 in which the casting is being made. The bottom plate 128 is preferably provided with ribs 133 similar to the ribs 83 described in connection with Figure 1 to 40 center the investment ring and hold the investment material slightly spaced from the plate 128, whereby air may escape more easily.

45 A latch member 134 is pivotally mounted on a non-rotatable cross bar 135 and has hook portions 136 adapted to engage with hook means 137 on the crucible housing 107 to hold the crucible housing in a horizontal or an inclined position. A stop pin 138 carried by the latch member 134 is adapted to engage with a fixed stop collar 139 50 on the bar 135 to maintain the latch member 134 in a substantially horizontal position, whereby it will automatically engage with the hook means 137 when the crucible housing is swung upwardly from a vertical toward a horizontal position. 55

60 In the operation of the device shown in Fig. 4 the gold alloy or like metal is melted in the crucible with the parts in the position shown by full lines. Before starting to heat this metal the valve 113 is opened and inert gas turned on. Enough of this gas will enter through perforation 122 to drive out the air and insure that the heating and melting is done in the presence of the inert gas. When the metal to be cast is 65 properly melted the latch member 134 is released. This causes the crucible housing 107 and furnace 123 to swing down into a position as shown by dot and dash lines, pouring the molten metal into the recess 84 in the end of the investment and moving the ports 120 and 121 into 70 registration with each other so as to quickly admit enough inert gas to build up a pressure and drive the molten metal into the mold. 75

75 The furnace housing 123 may be swung downwardly into an inclined position as shown frag-

mentarily by dot and dash lines in Fig. 4 to afford easy access to the interior of both the furnace and the crucible. Also the crucible may be used for heat treating or tempering gold or like parts and when it is to be so used a separate closure member 140, Fig. 7, having pin means 141 projecting perpendicularly therefrom is applied to the open end portion of the crucible by inserting the pin means 141 in holes 142, which are provided in the crucible housing 107. One of these holes is shown by broken lines in Fig. 4. This closure member is thus supported so that it may be positioned against the end of the lining 114 to completely close the opening to the crucible chamber or it may be moved outwardly therefrom to allow the escape of some heat. This provides a heat control means which is useful where it is desired to permit slow cooling of a part. This makes it possible to use the crucible for baking porcelain parts, or for heat treating metal or other parts. The same door 140 can be used in any other furnace shown here also.

Fig. 8 shows a modified form of the invention in which a furnace 143 and crucible 144 are both mounted on hinge means 145 for swinging movement through an angle of approximately ninety degrees (90°) and in which the crucible 144 is supported on an arm 146, which is slideable and angularly movable on a guide member 147. Guide member 147 is rigidly connected with a separable base portion 148 upon which the furnace 143 is mounted. The hinge 145 connects the furnace base 148 with a base support 150. The furnace 143 has a lining 151 provided with electric heating coil means 152. An investment ring 27' with investment material therein is shown in the furnace 143. This investment ring 27' is plane and flat and free from notches on the ends and the inner end portion of the crucible makes sealing contact with the end of this investment ring 27'.

Pyrometer means 30 is provided in the bottom portion of the furnace 143 to contact the investment material 28 and accurately register the temperature thereof. Preferably the furnace 143 is separately connected with the base portion 148 by plug means 153, whereby furnaces of different size may be plugged in on this same base and used in connection with the crucible portion 144. The electrical connections are also preferably made through the plug means 153. If a large furnace is used in the place of furnace 143, an opening in the hinged door on the furnace would be made by removing a removable port in the door the size of the crucible housing 144, thereby allowing the crucible 144 to extend into the door and contact with the investment ring 27'. The remaining outer portion of the door would then close the space on the face of the furnace 60 143 around crucible 144, which would be smaller than the opening in furnace 143.

A suitable conduit 154 is connected with the chamber within the crucible housing 144 through which inert gas may be admitted and the crucible housing 144 is provided with a sight tube 155 through which the condition of the metal used for casting may be observed. Preferably a transparent disc 149 is provided at the outer end of the sight tube 155. A sight tube of this nature may be used with any of the furnaces herein disclosed.

In the operation of the device shown in Fig. 8, when an investment ring 27' is to be inserted in or removed from the furnace the crucible is withdrawn from the mouth of the furnace and an-

gularly moved to one side of the mouth of said furnace. Also the furnace is angularly moved counterclockwise on hinge 145 substantially ninety degrees from the position shown in Fig. 8, so that the mouth of the furnace is uppermost, thereby permitting easy insertion and removal of the investment ring. After the investment ring has been inserted, the furnace and crucible may be angularly moved back into the position shown in Fig. 8, the metal to be melted placed in the crucible and the crucible moved into the end of the furnace against the end of the investment. The investment material may then be heated to the desired degree, inert gas having been admitted through the tube 78. After the metal is melted and the desired temperature of the investment material obtained, the furnace and crucible are angularly moved counterclockwise from the position shown in Fig. 8 to discharge the molten metal by gravity into the cavity in the investment material. At the same time a larger supply of inert gas will be admitted to help force the molten metal into the mold.

In Fig. 9 I have shown another modified form of my invention which is similar to the form shown in Fig. 8, except that the crucible is secured to the furnace door. In said Fig. 9, 156 is a furnace, which is pivotally mounted by horizontal pivot means 157 on a support 158. The furnace 156 has a lining 159 provided with electric heating coils 160 and has pyrometer means 30 in the bottom portion thereof. An investment ring 27' within the furnace 156 has investment material 28 therein. A furnace door 162 is pivotally secured to the furnace 156 by hinge means 163 and has annular steps 164 on its inner side adapted to fit within investment rings 27' of different size, which are positioned within the furnace. The inner side of the door can be flat in place of having the steps 164, if desired. 165 is a crucible housing integral with or secured to the furnace door 162 and positioned on the outer side of said door 162 and adapted to communicate with the inside of the furnace. The crucible 165 has a sight tube 166 and is connected with an inert gas conduit 167 and has heating element means 168. Screw means 169 is provided in the bottom of the furnace for pressing the investment ring 27' firmly against the door 162. The investment ring 27' in this instance does not have any notches in the ends thereof.

The furnace 156 is turned into an upright position at right angles from the position shown in Fig. 9 and the door 162 is opened when an investment ring is to be placed in or taken out of the furnace. After a properly conditioned investment ring has been correctly placed in the furnace 156 and metal, which is to be used in casting, has been placed in the crucible 165, the door 162 is closed against the investment ring with a step portion 164 of proper size on said door projecting slightly into the end of the investment ring and said door is fastened in closed position by fastening means 170. The furnace 156 and crucible 165 are then angularly moved into the position shown in Fig. 9 and inert gas is admitted to drive out the air. As soon as the investment material has been heated to the proper temperature and the metal reduced to a molten and fluid state, the furnace 156 and crucible 165 are angularly moved back into an upright position, allowing the molten metal to flow by gravity into the mold cavity in the investment material.

Fig. 9 also shows a means for supplying inert

gas to the interior of the furnace 156 when the crucible is disconnected therefrom and similar inert gas supply means may be connected with the other furnaces herein disclosed. This inert 5 gas supply means comprises a hose 171 connected by readily detachable coupling means 172 with a valve 173 which is connected by a pipe 174 with a conduit 175 which leads to the interior of the furnace 156. This independent inert gas inlet 10 means to a furnace of this type makes it possible to heat treat metal or metal parts in the investment furnace in the presence of inert gas. Also this independent inert gas inlet makes it 15 possible to solder metal parts together in the furnace in the presence of a flow of inert gas, thereby eliminating the necessity of using a flux to prevent oxidation and contamination of the metal parts during the soldering process. To facilitate thus using the furnace for soldering it 20 is desirable to provide a table or stand to be used in the furnace to support the parts to be soldered. Such a table is shown in Fig. 19 and comprises a table top 176 adapted to be supported at different elevations within the furnace by adjust- 25 able supporting means. Preferably this supporting means is in the nature of a plurality of interchangeable rings 177 of different height. By providing bevels 178 on the ends of these rings to interfit each other when the rings are placed 30 end to end I provide a more stable support. Obviously the ends of these rings may be flat or may be shaped differently than shown. A circular groove 179 is provided in the bottom side of the table top to receive the beveled end of the 35 uppermost ring 177. By using more or less rings and different combinations of rings the elevation of the table top may be varied to suit the requirements of the work. When using the furnace for soldering, the parts to be soldered will preferably 40 be placed on the table within the furnace, a cover will be applied to the furnace and the parts brought up to a temperature just sufficient to melt the solder to be used. Under these conditions the solder will flow very freely and a 45 superior quality of soldering work can be done without using fluxes. This eliminates the necessity for electric welding in many instances. The table may be used to support any material to be heat treated or worked on in the furnace.

50 The electric heating means in any or all of the crucibles 52, 93, 114, 144, and 165 may employ grooves, like the grooves 25 shown in Figure 1, for the reception of the heating elements.

I have shown and described resistance type 55 electric heating means in all of the crucibles herein disclosed, but it will be understood that other types of electric heating means may be employed, as for instance, the well known induction type electric heater may be used instead 60 of the type disclosed in the drawings.

Obviously, changes may be made in the forms, dimensions and arrangement of the parts of my invention, without departing from the principle thereof, the above setting forth only preferred 65 forms of embodiment.

I claim:

1. Mechanism of the class described comprising a furnace having a heating receptacle adapted to receive an investment ring containing investment material, said investment material having a recess extending from the exterior thereof inwardly; and pyrometer means longitudinally movable through a wall of said furnace positioned to extend into the recess in the investment material.

2. Mechanism of the class described comprising a furnace having a heating receptacle adapted to receive an investment ring containing investment material, said investment material having a recess extending from the exterior thereof inwardly for the reception of pyrometer means; a pyrometer member longitudinally movable through a wall of said furnace positioned to extend into said recess in the investment material; and resilient means urging said pyrometer member into said recess in said investment material.

3. Mechanism of the class described comprising a furnace; a crucible housing positioned in registration with said furnace when in a casting 15 position, said crucible housing having a crucible chamber provided therein; a cup shaped crucible pivotally mounted in said crucible chamber and movable from a metal holding to a metal discharging position; gas conduit means in said 20 crucible housing directed toward said crucible whereby said crucible may be moved into a metal discharging position by the inlet of gas through said conduit; and gas pressure supply means connected with said gas conduit means.

4. Mechanism of the class described comprising a furnace having a heating receptacle; a plurality of radial ribs in the bottom portion of said heating receptacle, some of said ribs being relatively offset at angles greater or less than one 30 hundred eighty degrees; and investment ring means having investment material therein, said investment ring means and investment material having radial grooves in the bottom end portion thereof corresponding in positions to the radial 35 ribs in the bottom portion of said heating receptacle and fitting over said ribs when the investment ring means is inserted into the heating receptacle, whereby said investment ring means is correctly centered in said heating receptacle. 40

5. Mechanism of the class described comprising a furnace having a heating receptacle adapted to receive an investment ring containing investment material; a crucible housing having a crucible chamber therein; said furnace and said 45 crucible housing being relatively movable into end to end relation to position the heating chamber and the crucible chamber in registration; a lining member in said crucible chamber supported for movement toward and away from 50 the investment material in said furnace; lining member moving means connected with said lining member; and a crucible pivotally supported in said lining member whereby it may be moved into a discharging position.

6. Mechanism of the class described comprising an upright furnace having a heating receptacle adapted to receive an investment ring containing investment material; a crucible housing having a crucible chamber therein and having a passageway extending from said crucible chamber to the opposite side of said crucible housing; means connecting said furnace and said crucible housing for relative movement, whereby said crucible chamber and said heating receptacle may be positioned in registration with each other; a hollow lining member movably disposed in said crucible chamber for adjustment into sealing engagement with investment material in rings of different size within said furnace, said lining member having a shank extending into said passageway; lining member moving means connected with said shank and a crucible supported in said lining member and movable into a discharging position.

7. Mechanism of the class described comprising a crucible housing; horizontal pivot means supporting said crucible housing for swinging movement; releasable means positioned to support said crucible housing in a substantially horizontal position; crucible means within said crucible housing having a discharge opening at one end portion of said crucible housing; and a furnace hinged to said crucible housing for swinging movement into and out of axial alignment therewith, said furnace having a heating receptacle adapted to receive an investment material and said furnace being swingingly movable along with said crucible housing.
8. Mechanism of the class described comprising a casting furnace having a receptacle for the reception of a casting investment; a crucible housing connected with said casting furnace and having a crucible chamber communicating with the furnace; means pivotally supporting said crucible housing and said furnace for movement between a substantially horizontal metal melting position and a substantially vertical metal casting position; gas pressure supply means connected with said crucible chamber; and valve means operatively connected with said pivotal supporting means controlling said gas pressure supply means, said valve means being adapted to be opened upon movement of said crucible means into a substantially vertical position, whereby gas under pressure will be admitted to said crucible chamber and said furnace simultaneously with the pouring of the molten metal into the casting investment.
9. Mechanism of the class described comprising a furnace having a heating receptacle adapted to receive an investment ring containing investment material; hinge means supporting said furnace for angular movement between a position in which the axis of said furnace is substantially horizontal and a position in which the axis of said furnace is substantially vertical; a guide member angularly movable with said furnace and extending substantially parallel to the axis thereof; and a crucible member supported on said guide member for movement toward and away from said furnace and adapted to register with said heating receptacle when in a casting position, whereby molten metal from said crucible member will be discharged into investment material in said heating receptacle when said furnace is angularly moved into a substantially vertical position.
10. Mechanism of the class described comprising a furnace having a heating receptacle adapted to receive an investment ring containing investment material; pivot means supporting said furnace for angular movement between a substantially horizontal and a substantially vertical position; a door member hinged to the furnace and movable between an open and a closed position relative to said heating receptacle; and crucible means carried by said door member and having a discharge opening extending through said door member and positioned to discharge molten metal from said crucible into investment material in said heating receptacle when said furnace is angularly moved into a substantially vertical position.
11. Dental casting apparatus comprising a closed receptacle; a chamber in said receptacle for receiving therein investment means; heating means for investment means in said chamber; a metal melting crucible in said receptacle operatively positioned relative to investment means in said chamber; means movably mounting said crucible providing a position for melting metal and a position for pouring molten metal into said investment means; heating means for said crucible; and externally positioned means controlling the operative position of the crucible relative to said investment means.
12. Dental casting apparatus comprising a closed receptacle; a chamber in said receptacle for receiving therein investment means; heating means for investment means in said chamber; a metal melting crucible in said receptacle operatively positioned relative to investment means in said chamber and having a position for melting and a position for pouring molten metal into said investment means; heating means for said crucible; and pivot means mounting said receptacle and the crucible therein for movement between the melting position and the pouring position of the crucible.
13. Mechanism of the class described comprising an upright furnace having a receptacle for the reception of casting investment means; heating means for said furnace; an upright support positioned at one side of said furnace; a crucible supporting arm longitudinally and rotatably movable on said upright support; and a crucible supported by said supporting arm for angular movement axially of said supporting arm, whereby said crucible may be moved vertically and transversely relative to said furnace and may be moved angularly on said supporting arm to facilitate access to the interior of said crucible.
